PUMP

Lewis E. Williams, Long Beach, Calif., assignor to
 Willhoit Engineering Corporation, Hawthorne,
 Calif., a corporation of California

Application October 31, 1942, Serial No. 464,055

4 Claims. (Cl. 103—185)

This invention relates to incendiary pumps, and more particularly to a construction of a double acting hand-pump adapted for developing a spray of water or other fluid under pressure for use in extinguishing incendiary bombs or other like purposes.

It is an object of my invention to produce a hand-pump of the double acting type applicable for the development of pressure and for the dispersing of a fluid through a spray nozzle or the like under pressure, which pump is adapted to be held in the hands and to take fluid from any suitable source, as from a pail or the like.

Another object of my invention is to provide a double acting hand-pump of portable structure and adapted to be used in the development of relatively high pressures for the spraying of water or other fluids in a fine spray under relatively high pressures.

Other objects and advantages of this invention it is believed will be apparent from the following detailed description of a preferred embodiment thereof as illustrated in the accompanying drawing.

In the drawing the figure is a sectional elevation of an incendiary pump embodying my invention.

In the preferred embodiment of my invention as illustrated in the accompanying drawing, the pump includes a barrel 1, the opposed ends of which form cylinders 2 and 3 in which pistons 4 and 5 are mounted. The pistons 4 and 5 are of like construction and each includes a disc 6 and a follower 7 between which there is mounted a cup 8 having an inturned wiping periphery 9. The pistons thus formed are secured to piston rods 10 and 11. Each of the piston rods 10 and 11 are secured to guide discs 12 and 13 mounted to move with the pistons in the respective cylinders. The piston rods 10 and 11 are connected by means of links 14 and 15 to a crank 16. The crank 16 is formed with a shaft extension 17 which extends through the wall of the barrel 1. On the exterior the shaft 17 is formed integral with a handle shank 18 to which an operating handle 19 is secured. The length of the shank 18 is many times the length of the crank 16 in order to obtain the mechanical advantage of the difference in the length of the levers.

An inlet as indicated at 20 is formed in the barrel 1 between the cylinders 2 and 3 and to this inlet may be secured a flexible hose 21 which may be dropped into a bucket 22 containing the liquid or fluid to be pumped.

Each of the cylinders 2 and 3 is provided with

a cylinder head 23 and 24. Formed exterior of the barrel 1 is a conduit 25 which connects the cylinder 2 above the piston 4 with the cylinder 3 above the piston 5. Mounted in the outlet from the cylinder to the conduit 25 is a check valve 26, and mounted in the outlet from the cylinder 3 to the conduit 25 is a check valve 27. The conduit 25 is formed with a threaded neck 28 to receive a suitable nozzle 29.

The relationship of the links 14 and 15 with the crank 16 and the piston rods 10 and 11 provides that when the piston 4 is on the suction stroke, the piston 5 is on the pressure discharge stroke, and vice versa. By this means a double acting pump is provided which insures continuous discharge of fluid through the neck 28.

The double acting pump embodying my invention is of the portable hand-operated type and in order to permit the operator to support the pump during his actuation of the operating handle 19, a handle 30 is secured to the barrel 1 in position removed from the handle 19.

The operation of the pump embodying my invention is: assuming the parts in the position as illustrated in the figure and the handle 19 being rotated in a clockwise direction, the piston 5 is at the completion of the discharge stroke while the piston 4 is at the start of the discharge stroke. As the handle is rotated, fluid within the cylinder 2 above the piston 4 is forced by the check valve 26 through the conduit 25 and out the threaded neck 28. As the piston 5 moved toward the left, suction is developed in the cylinder 2 and the check valve 27 is closed. Fluid from within the cylinder is then drawn by the cup 8 as the cup 8 is of flexible construction; its curved periphery 9 moves away from the wall of the cylinder 3 allowing the fluid under atmospheric pressure within the barrel 1 to pass into the cylinder 3 because of the reduction of pressure in the cylinder 3. On continued rotation of the handle 19, the piston 5 completes its suction stroke and reverses in direction. When it reverses in direction, the fluid within the cylinder 3 exerts a pressure against the curved periphery 9 of the cup 8 forcing the cup against the wall of the cylinder in fluid-tight relation, with the result that the fluid is forced by the check valve 27 and from the neck. The operation of the piston within the cylinder 2 is precisely the same as set forth with respect to the operation of the piston 5. The guides 13 may be either loosely fitted within the barrel 1 as to permit the fluid being pumped to pass around their edges,

or may be formed with a plurality of fluid apertures such as indicated at 31. One of the particular advantages embodying my invention is that it provides a continuously discharging hand-operated portable pump which may be used for the development of fluid under pressure to a spray nozzle for extinguishing incendiary bombs or the like. The pump may also be used as a double acting pump for the development of pressure in other fluids such as air and under such conditions of use, may be used for pumping up pneumatic tires or the like.

Having fully described my invention, it is to be understood that I do not wish to be limited to the details herein set forth, but my invention is of the full scope of the appended claims.

I claim:

1. In a hand pump, the combination of a barrel forming opposed cylinders, flexible cup packing pistons in said cylinders, connecting rods secured to the pistons, guide discs carried by said rods within said barrel, a crank mounted within the barrel, links connecting the crank with said piston rods, fluid passage means exterior to the barrel connecting the heads of the cylinders, an inlet to the barrel between the cylinders, check valves mounted in the passage from the cylinder heads to the connecting passage, and an elongated operating handle exterior to the barrel and connected with the crank for rotation thereof.

2. In a hand pump, the combination of a barrel forming opposed cylinders, flexible cup packing pistons in said cylinders, connecting rods secured to the pistons, guide discs carried by said

rods within said barrel, a crank journaled within the barrel, links connecting the crank with the piston rods, fluid passage means exterior to the barrel connecting the heads of the cylinders, 5 an operating crank handle for rotation of the crank, and a handle secured to the barrel at one end removed from the position of the crank.

3. In a hand pump, the combination of a barrel forming opposed cylinders, flexible cup packing pistons in said cylinders, connecting rods secured to the pistons, guide means for said rods within the barrel, a crank mounted within the barrel and connected through said guide means with the pistons, a fluid passage exterior to the 10 barrel connecting the heads of the cylinders, a check valve for each of the cylinder head discharge passages to said exterior passage, and an inlet to the barrel between the cylinders.

4. In a hand pump, the combination of a barrel forming opposed cylinders, flexible cup packing pistons in said cylinders, connecting rods secured to the pistons, guide discs carried by said rods within said barrel, a crank mounted within the barrel, links connecting the crank with said 15 piston, the crank being journaled on a shaft within the barrel, an operating arm secured to the shaft exterior of the cylinder and having an operating handle secured thereto, the length of the operating arm being elongated with reference 20 to the throw of the crank to provide for mechanical advantage of hand rotation of the operating handle with reference to the rotation of the crank.

LEWIS E. WILLIAMS.
